SPARK GAP DEVICE

John W. Kalb, Barberton, Ohio, assignor to The Ohio Brass Company, Mansfield, Ohio, a corporation of New Jersey

Application January 3, 1951, Serial No. 204,242

12 Claims. (CL. 313—268)

1 This invention relates to a spark-gap device for a lightning-arrester or the like.

Spark-gap devices are well known in the art. They are ordinarily built up of metal electrodes separated by insulating spacers. The electrodes are dished in one or both directions to produce areas which approach one another and form the spark gaps. In certain constructions there is a central opening through the electrodes in which a rod of insulating material is located. It is generally advantageous for economy in manufacture to have all of the electrodes uniform and to alternate them, as by turning one up and the other down, to form the spark gaps. The more widely spaced portions accommodate the spacers.

The spacers and central rods are composed of materials having sufficiently high dielectric strength to insulate the electrodes of the spark gaps from one another. In some spark-gap devices the insulating members are composed of a material such as porcelain having a dielectric constant of about 7, while in others titanium dioxide (rutile) is used to form a ceramic having excellent insulating properties and high dielectric constant exceeding 20. All such members composed of materials suitable for the purpose described, are referred to herein as insulators, although some have better insulating properties than others.

The space between the electrodes at the spark gaps must be sufficient to prevent sparking at 60-cycle or normal frequency breakdown voltage but not so great as to prevent a discharge across the gap spaces when a high voltage differential is placed on the opposite terminals of the arrester or other piece of equipment in which the spark-gap unit is located. In a spark-gap device using a plurality of spark-gaps the spark gap space between certain of the electrodes may be greater than between other spark gaps, although this is not essential.

In the spark-gap units of this invention there are discharge or ionizing tips associated with the electrodes which produce a corona discharge over a portion of the surface of the spacers, and insure spark-over at a uniform predetermined low voltage. These tips may be formed separately from the electrodes and then attached to them, but generally they will be formed as an integral part of the electrodes.

When an electrical surge is impressed on a spark-gap device and before its voltage becomes sufficient to discharge across the gap spaces in a spark-gap device, the electrodes induce a voltage differential in each spacer. There is a volt-

age gradient from one end of each spacer to the other. By providing some or all of the electrodes with one or more ionizing tips, and locating these tips contiguous to portions of the spacers maintained at a different voltage from the respective tips, a corona discharge occurs about the tips and over the surface of the spacers around the tips. This ionizes the air or gas in which the discharge occurs, furnishing free electrons which radiate out into the gap space causing the gap to spark over at a consistent and predictable low voltage. Such a gap is very fast and has a low impulse ratio.

2 In the absence of electrons the gap will not spark over at this consistently low voltage, but a higher voltage is necessary in order to induce the spark, and this delays the spark. The potential of the voltage required when there is no positive supply of electrons may vary over a wide range. By insuring the presence of free electrons in the spark gap area the spark always forms in the shortest possible time and at the lowest voltage, and this voltage is consistent and predictable.

5 In order to produce a corona discharge, it is necessary that there be a voltage drop between the ionizing tip and the surface of the spacer. It is immaterial which is at the higher voltage. The voltage drop over the length of the spacer is the same as between the electrodes contacting it, and each ionizing tip is located contiguous to a portion of the spacer which has a different voltage from the electrode to which the ionizing tip is connected.

10 The invention will be further described in connection with the accompanying drawings which illustrate various adaptations of the invention, but it is to be understood that the scope of the invention is not limited thereto. In the description of these drawings the insulating material will sometimes be referred to as of porcelain, but it is to be understood that rutile and other materials known in the art may be used instead of porcelain. In locating the ionizing tips contiguous to the porcelain, etc. it is to be understood that they may touch, be pressed against, or be slightly spaced from it. Whatever the difference in effect, any of these arrangements may be used in carrying out the invention. The tips

15 are preferably pointed but may be blunt provided they give a corona discharge instead of inducing their own potential on the portions of the spacers contiguous to them. The electrodes are preferably fabricated from sheets of high brass, in a single operation, the ionizing tips be-

ing simultaneously formed integrally with the electrodes.

In the drawings—

Fig. 1 is a vertical view in partial section through a lightning arrester which includes a 5 spark-gap device of this invention;

Fig. 2 is a cross section of the spark-gap device taken through one of the spacers, on the line 2—2 of Fig. 1;

Fig. 3 is a cross section of the spark-gap device 10 on the line 3—3 of Fig. 1 showing a top plan view of one of the electrodes;

Fig. 4 is a vertical section through an alternative spark-gap unit;

Fig. 5 is a cross section on the line 5—5 of 15 Fig. 4 showing a top plan view of one of the upper electrodes partially broken away at the center so as to show the lower electrode below it;

Fig. 6 is a vertical section through another form of spark-gap unit; and

Fig. 7 is a cross section on the line 7—7 of 20 Fig. 6 showing a top plan view of one of the electrodes.

Although the spark-gap device may be accommodated to a lightning arrester of any type, or to other suitable equipment, it is shown herein as enclosed in a porcelain housing 1 with metal end caps 2 and 3. The stamped sheet metal end closures 4 may be united to the housing at 5 in any suitable manner, as by interlocking or by the use of adhesives, etc. Around the opening at each end of the housing is an annular cushion 8 of rubber or other resilient material. The spring plates 9 which rest against the shoulder 10 of each end cap comprise annular discs of spring metal. The end caps 2 and 3 are each provided with a flange 11 and are held in place by cement 12 between the flanges and housing. When the end caps are in position the spring plates 9 apply pressure to the end closures 4 at the cushions 8 maintaining the cushions under pressure. This end construction seals the interior of the housing and the air may be replaced by an inert gas if desirable. The rubber cushions 13 prevent cement 12 or the like entering the space between the end caps and the end caps and the end closures 4.

The transmission line 20 which is protected by the lightning arrester is connected to the upper end cap by the metal cable connector and bolt 21 and a high voltage surge and the follow-up current flows from the end cap 2 and the spring plate 9, down through the end closure 4 to the metal contact disc 23. From here the discharge flows through the spring 24 and shunt 25 to the contact disc 26. It then flows through the spark-gap device to the contact disc 29 and then through the valve blocks 30 of any usual type to the bottom contact plate 31, and thence through the bottom closure means of the lightning arrester and conductor 35 to the ground G.

The spark-gap device of Figs. 1-3 is formed of a central porcelain column 40 and a plurality of spark-gap units, each unit being composed of an upper and lower electrode 41 and 42, respectively, which are identical in structure. The electrodes of each unit are separated by an annular spacer 46 of porcelain or other insulating material, the electrode 41 being placed with the ionizing tips 43 pointing down, and the electrode 42 being placed with the ionizing tips 44 pointing up, all tips terminating contiguous a spacer 46 at a position a sufficient distance from the top or bottom edge of the spacer to be at a different

potential from the electrode from which it projects.

When an electric surge is impressed on the spark-gap device, whether or not it is caused by lightning, the difference in potential between the respective ionizing tips and the portions of the spacers adjacent to them produces corona discharge over the surface of the spacer surrounding each ionizing tip. Ions produced in this manner radiate into the gap space, and cause the gap to break down almost immediately at a minimum voltage.

Although the drawings contemplate having several ionizing tips project inwardly from each electrode, one tip at each electrode or each pair of electrodes is all that is necessary, if it terminates close enough to the spacer. Furthermore, if ionizing tips are provided at only about ten per cent of the spark gaps, these gaps will break down almost immediately and the voltage differential over the remaining gaps will cause them to discharge rapidly and at low voltage. Several ionizing tips are as easily formed on each electrode as one. When each electrode has several tips, the electrodes of each unit are advantageously so positioned that the tips of one electrode are uniformly spaced circumferentially with respect to those of the other electrode as shown by tips 43 and 44 in Figs. 2 and 3 in which each electrode is provided with three tips.

In the spark-gap unit shown in Figs. 4 and 5 there is no central column and there is no opening in the central portion of the several electrodes. During the stamping operation the ionizing tips 61 are formed as an integral part of each electrode leaving openings 62, and the tips are bent outwardly to contact the annular spacer 63 formed of porcelain or other suitable material. The electrodes are formed in duplicate and arranged in pairs such that the central dished portions alternate to form a depressed portion 64 in each upper electrode 65 and a raised portion 66 in each lower electrode 67. These dished portions form the spark gaps. The ionizing tips are so formed that they terminate contiguous to the middle portion of the inner wall of the spacer 63 in the plane of the gap space. The voltage at these points on the spacer is intermediate that of the top and bottom of the spacer both of which contact wide areas of the electrodes and are at the voltages of the respective electrodes. When an electric surge is impressed on the spark-gap, corona occurs around the ionizing tips, forming ions which radiate into the spark-gap space and effect a rapid, low-voltage discharge and a low impulse ratio. The electrodes are each shown with two tips which are positioned 90° apart.

Figures 6 and 7 show an alternative type of spark-gap unit in which there is a center rod 70 of porcelain or other suitable material located centrally of the unit. Around this column are positioned the electrodes 71 and an annular insulating spacers 72. Each unit comprises a pair of spaced electrodes and an insulating spacer. When more than one gap unit is used there are two electrodes in electrical contact between each two spacers. The electrodes 71 of each unit are duplicates and flare outwardly, forming an annular spark gap between the portions 73 of each spaced pair of electrodes. Three ionizing tips 74 are formed integrally with each electrode 71 leaving openings 75, and the tips 76 are shown projecting inwardly from each elec-

trode and terminating contiguous to the mid portion of the spacer in the plane of the gap space where the voltage is intermediate that of the two electrodes of the unit. Corona discharge forms at the end of each tip, as in the other spark-gap units.

Some spark-gap devices are formed of centrally dished electrodes and flat electrodes separated by annular spacers. Upper and lower electrodes are paired in face-to-face contact around their periphery where they are contacted above and below by annular spacers, much as shown in Fig. 4. However, the spacers are not relatively as high as that shown in Fig. 4, but approximately half as high, and a flat electrode is interposed between each two spacers located between each pair of dished electrodes. The dished portions of the electrodes on opposite sides of each flat electrode form separate spark gaps with it. Such spark-gap devices are known in the art. Ionizing tips may be formed on the flat electrodes or the dished electrodes or both, terminating adjacent the spacers, in or near the planes of the spark gaps. Because the spark gaps are located at the opposite faces of the flat electrodes the ionizing tips preferably project from the dished electrodes.

Thus it will be evident that there are various ways of constructing spark-gap units in which the electrodes are arranged in spaced pairs with spark gap means between each pair and ionizing tips projecting therefrom in contiguous relation to insulating material having a dielectric constant in excess of unity, whereby a voltage drop occurs between each tip and the insulating material adjacent it. These conditions produce the desired corona discharge which results in ionization of the air or gas in a near-by spark gap, when a rapidly rising voltage is impressed upon the gap, thereby assisting in a rapid and consistently low voltage breakdown of the gap.

What I claim is:

1. In a spark-gap unit a spacer of insulating material, an electrode on each side of the spacer, the electrodes forming a spark gap between portions thereof which are spaced closer than the length of the spacer, and an ionizing tip projecting from at least one of the electrodes and which terminates contiguous to the spacer, whereby when a high voltage builds up over the spark gap, corona discharge forms on the surface of the spacer about the tip at a voltage less than the voltage required to cause a spark-over at the gap.

2. In a spark-gap unit an annular spacer, an electrode on each side of the spacer, the electrodes forming a spark gap between portions thereof which portions are spaced closer than the length of the spacer, and an ionizing tip projecting from at least one of the electrodes and which is of the same composition as the electrodes and which terminates contiguous to the spacer at a point whereby an overstressing of the air takes place at the point of contiguity between the spacer and the ionizing tip when a high voltage builds up over the spark-gap unit, thus producing a radiation at the said point of contiguity thereby causing a rapid spark-over of the gap.

3. A spark-gap unit formed of two sheet metal electrodes and held spaced apart by an annular spacer, at least one of the electrodes being bent toward the other into the space surrounded by the spacer, and an ionizing tip extending from

one of the electrodes and terminating contiguous to the inner surface of the spacer at a substantial distance from where the electrode contacts the spacer.

4. A spark-gap unit formed of two sheet metal electrodes and an insulating spacer, the electrodes being each formed with a depressed portion so positioned relative to one another as to form a spark gap therebetween located centrally of the spacer, and an ionizing tip projecting from at least one of the electrodes and terminating contiguous the inner surface of the spacer in the plane of the gap space.

5. A spark-gap device which includes a central column of insulating material, a plurality of annular insulating spacers encircling the column adjacent thereto, a pair of contacting electrodes between each two spacers, those electrodes held in separation by each spacer being so formed as to provide an annular spark-gap surrounding the spacer, an ionizing tip projecting from at least one of the electrodes and terminating contiguous to the outer wall of the included spacer at a point intermediate the spaced electrodes whereby when a high voltage builds up over the spark-gap device a corona discharge forms at the ionizing tip at a voltage less than the voltage required to cause a spark-over at any of the spark gaps.

6. A spark-gap device comprising a central insulating column, a plurality of annular sheet metal electrodes arranged in pairs and the electrodes of each pair held in spaced and insulated relation by a spacer therebetween, the electrodes being of greater diameter than the spacers and extending outwardly therefrom, a portion of each electrode which extends outwardly beyond the spacer adjacent it, being bent toward the other electrode of the pair whereby there is formed between each pair of electrodes a spark gap which encircles the spacer, and an ionizing tip which projects from at least one of the electrodes in at least one of the pairs of electrodes and terminates contiguous to the outer surface of the spacer a substantial distance from its top and bottom.

7. A spark-gap device comprising a central column of insulating material, a plurality of annular sheet metal electrodes arranged in pairs surrounding the column and an annular insulating spacer separating the electrodes of each pair, the electrodes extending outwardly from the spacers, a portion of each electrode which extends outwardly beyond its spacer being bent toward the middle of the spacer whereby a continuous spark gap is formed which encircles the spacer, and an ionizing tip extending from at least one of the electrodes and terminating in the plane of the gap space contiguous to the surface of the spacer.

8. A spark-gap unit comprising a pair of electrodes spaced apart and so formed as to provide a spark gap therebetween, insulating spacer means surrounding the spark gap and positioned between the electrodes holding them in spaced relation, and pointed ionizing means associated with at least one of the electrodes and having its point contiguous to the inner surface of the spacer means at a point intermediate the electrodes whereby the spark gap is caused to break down rapidly when a rapid increase in voltage is applied to the gap.

9. A spark-gap unit comprising a pair of electrodes spaced apart and so formed as to provide a spark gap therebetween, each electrode provided with a central opening registering with an

opening in the other electrode, an annular spacer member of insulating material positioned between the electrodes holding the electrodes in spaced relation, the central opening of the spacer means registering with those of the electrodes, and ionizing means projecting from one or both electrodes and terminating contiguous to the surface of the said spacer member intermediate the electrodes, for the purpose described.

10. A spark-gap unit comprising a pair of spaced-apart electrodes and an annular spacing member positioned between the electrodes holding them in spaced relation, the spacing member being formed of a ceramic with a dielectric constant in excess of unity, at least one of the electrodes formed with at least one projecting ionizing member terminating in a point, the ionizing member being so positioned relative to the spacing member that its point engages the inner surface of the spacing member extending between the electrodes at a point spaced from each electrode whereby ionizing radiation is effected in the gap.

11. A circular electrode for a spark-gap device having a flat outer portion with the central portion bent away from the plane of the outer por-

tion, and an ionizing tip associated with the latter portion and projecting from one face thereof and terminating at a position approximately above the inner edge of the flat portion.

12. A circular electrode for a spark gap unit with a central opening and a flat portion surrounding the opening and another portion surrounding the flat portion which is bent away from the plane of the flat portion to form part of a spark gap, and an ionizing tip which projects outwardly from one face thereof and terminates at a position approximately above the outer edge of the flat portion.
